UNITED STATES PATENT OFFICE.

RUBIN MAINKER, OF BAYONNE, NEW JERSEY, ASSIGNOR OF ONE-HALF TO MAX LICHTIGER, OF NEWARK, NEW JERSEY.

CORNER-FASTENER FOR BEDSTEADS.

1,047,669.

Specification of Letters Patent. Patented Dec. 17, 1912.

Application filed October 16, 1912. Serial No. 725,974.

To all whom it may concern:

Be it known that I, RUBIN MAINKER, a citizen of the United States, residing at Bayonne, in the county of Hudson and State of New Jersey, have invented certain new and useful Improvements in Corner-Fasteners for Bedsteads; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in corner post fastenings for metal bedsteads; and, the present invention relates, more particularly, to a novel means for securing to the upright posts of brass or iron bedsteads, the bracket-members which are used for supporting the longitudinal side frames or irons of the bedstead.

My improved construction is of the type in which the parts are wedged together by the employment of a lock-plate, which in the art is sometimes called a washer, and a wedge-shaped key, the parts being arranged in such a manner that the said key is permanently, but movably connected with the said lock-plate, and is therefore in the proper position with the lock-plate, so that the key can be readily brought into its holding or locked engagement with the bracket-member which is to be fastened to the post, without the use of cumbersome tools, or the tedious operation of dropping the key through the long interior of the tubular post, in the endeavor of causing the key to enter the opening or hole in the tongue of the bracket-member which is to be connected with and secured to the bed-post.

The present invention, therefore, has for its principal object to provide a novel and simply constructed means for keying or wedging bracket-members to the tubular posts of metal bedsteads, the arrangement and construction of the parts being such, that the wedge or key is in its relative position with the parts which are to be connected, that all that is necessary is to merely pull the positioned key or wedge in a downward direction, whereby it is easily brought into its locking relation with the key-receiving

lug of the bracket-member, and co-acts with the same for firmly binding and locking the bracket-member in its normal relation with the bed-post.

The invention has for its further object to provide simplicity in the construction of the parts and ease of assembling the same, the parts being of such form that they are always in their relative positions for quick assembling and consequent economy in the manufacture of metal bedsteads, at the same time producing great strength and rigidity, as well as permanence in securing the assembled parts, and also to provide a wedge-
construction for the purposes stated which is not difficult to assemble.

Other objects of this invention not at this time more particularly enumerated will be clearly understood from the following detailed description of the present invention.

With the various objects of the present invention in view, the invention consists, primarily, in a novel means for securing to the upright tubular or hollow posts of bedsteads, the bracket-like members which are used for supporting the longitudinal side-frames or irons; and, the invention consists, furthermore, in the novel arrangements and combinations of the various devices and parts, as well as in the details of the construction of the same, all of which will be more fully described in the clauses of the claims which are appended to and which form an essential part of this specification.

The invention is clearly illustrated in the accompanying drawings, in which:—

Figure 1 is a vertical sectional representation of a portion of a hollow or tubular bed-post, and a bracket-member secured thereto, said view showing also in connection with said post and bracket-member, and in vertical section, a lock-plate within said post and a key or wedge, slidably connected with said lock-plate, all of the said parts being represented in their assembled and locked relations, and illustrating a securing means showing one embodiment of the principles of the present invention. Fig. 2 is a similar sectional representation of the several parts illustrated in said Fig. 1, but illustrating the key or wedge in its normal position with relation to the lock-plate, before being dropped into its holding engagement with the loop-shaped end of the bracket-member which is to be secured to the hol-

low or tubular bed-post. Fig. 3 is a top or plan view of the various parts represented in said Fig. 1, with the hollow or tubular post represented in transverse section; Fig. 4 is a horizontal section, said section being taken on line 4—4 in said Fig. 1; and Fig. 5 is a vertical section of the parts, said section being taken on line 5—5 in said Fig. 1, looking in the direction of the arrow *x*. Fig. 6 is a transverse vertical section of a portion of a hollow or tubular bed-post and a sectional representation of a bracket-member about to be secured to said post, said view showing within said post, and in elevation, a lock-plate and a key or wedge, in its raised relation with said lock-plate, all illustrating a modified construction of securing means, embodying the principles of the present invention; and Fig. 7 is a vertical section of the parts represented in said Fig. 6, said section being taken on line 7—7 in said Fig. 6, looking in the direction of the arrow *y*. Fig. 8 is a similar sectional representation of the same parts, taken on the same line in said Fig. 6, but illustrating the various parts in their assembled and locked relation; and Fig. 9 is a horizontal sectional representation, taken on line 9—9 in said Fig. 6, looking in the direction of the arrow *z*.

Similar characters of reference are employed in all of the above described views, to indicate corresponding parts.

Referring now to Figs. 1 to 5 inclusive of the drawings, the reference-character 1 indicates a portion of a tubular or hollow corner post of a bedstead, that shown in the accompanying drawings being of the usual cylindrical form, but it will be evident that the tubing of which the post is made may be of any other desired cross-section. At the proper point where the bracket-member 2 is to be connected or joined to the said post, the latter is provided with a suitably formed slot or opening 3. Suitably disposed within the interior of said tubular or hollow post 1 is a correspondingly shaped lock-plate, as 4, sometimes called the "washer," the main body-portion of this plate in the present instance being curved, so as to provide a pair of wing-like members 5 and 6 which conform to and register with the inner surface-portions of the said post 1, substantially as illustrated in said Figs. 1, 2, 3, 4 and 5 of the drawings. The main body-portion of the said lock-plate 4 is likewise provided with a slot or opening 7 of the same conformation, substantially, as that of the previously-mentioned slot or opening 3, said slot or opening 7 being adapted to be brought into registration with the said slot or opening 3, for the purposes to be presently more fully set forth. Extending in an upward direction from the said main body-portion of the said lock-

plate 4 is an extension, as 8, said extension being formed with a pair of vertically extending side-lugs 9 and 10, which project forwardly in the direction toward the longitudinal central axis of the post, and are also slightly angularly arranged so as to project at their vertical marginal edges toward each other, and thereby provide a suitable guide in which is slidably retained a suitably formed key or wedge, as 11. In that surface of the said key or wedge 11 which is adjacent to the inner surface of the post 1, and also adjacent to the inner surface-portions of the main body-portion of the lock-plate 4 and its extension 8, the said key or wedge is formed with a groove or channel, as 12, said groove or channel, however, being shorter than the entire length of the key or wedge 11, from top to bottom, as at 13 and 14, see Figs. 1 and 2 of the drawings, said portions 13 and 14 forming a pair of stops for limiting the sliding movements of the said key or wedge, in either direction, in the previously-mentioned guide of the lock-plate 4, as will be presently described. In order to limit the sliding movement of said key or wedge in said guide, the extension 8 which forms a part of said guide is provided with an inwardly projecting stud, projection, or protuberance, as 15, which may form an integral part of said extension 8, said stud, projection, or protuberance 15 projecting into the said groove or channel 12, so as to prevent the withdrawal or displacement of the key or wedge vertically from its slidably connected relation with the lock-plate and its guide, and the side-lugs 9 and 10 of the guide also preventing any displacement of the key or wedge 11 laterally from the guide, as will be clearly evident of an inspection of Figs. 3 and 5 of the drawings, on account of the correspondingly formed tapering or inclined and angular sides of the key or wedge. The previously-mentioned bracket-member 2 is preferably made with a concave or other suitably shaped end-face, as 17, adapted to register with the outer surface-portion of the post 1, and extending from said end-face 17 is a tongue-like member or extension, as 18, which is provided with a suitably shaped key or wedge-receiving opening, as 19. The said tongue or extension 18 is adapted to be inserted into and passes through the registering slots or openings 3 and 7 of the post 1 and the lock-plate 4, respectively, so that the opening 19 of said tongue or extension 18 is brought directly beneath and in alinement with the said lock-pin, key, or wedge 11, when the latter is in its normally raised position indicated in Fig. 2 of the drawings. The various parts hereinabove described are caused to assume the relative positions indicated in said Fig. 2, by inverting or turning up- 130

side down the post 1, whereby the lock-pin, key or wedge 11 has been permitted to drop into what may be termed its raised position, the bed-post is again reversed or turned around so as to be presented in its normal upright position, so that the lock-pin, key or wedge 11 will drop down and will enter the hole or opening 19 of the tongue or extension 18 of the bracket-member 2, as will be clearly evident. The lock-pin, key, or wedge 11 being tapered, the inclined portions of the same will draw the lug, tongue, or extension 18 in an inward direction toward the center of the interior of hollow or tubular post 1, and consequently will cause a tight binding relation between the bracket-member 2 and the post 1. By inserting a rod or other suitable means within the hollow or tubular bed-post, and against the top or upper end-portion of the lock-pin, key or wedge, and then striking said rod or other means a smart blow, the lock-pin, key, or wedge is firmly driven in a downward direction, into its tightening and wedging or locking relation with the lug, tongue, or extension 18, whereby the bracket-member 2 is firmly and positively secured in its side-frame receiving relation upon the hollow or tubular bed-post 1, as will be clearly understood from the foregoing description, and from an inspection of said several Figs. 1, 2, 3, 4 and 5 of the drawings.

Referring now to the modified corner-post fastening illustrated in Figs. 6 to 9 inclusive, the reference-character 20 indicates the hollow or tubular corner-post, the said post being provided with a slot or opening 21, and 22 indicates the bracket-member which is of the same general construction hereinbefore described, the said bracket-member being formed with a key or wedge-receiving lug, tongue or extension 23 in which there is a hole or opening 24. Suitably disposed within the interior of said tubular or hollow part 20 is a correspondingly shaped lock-plate, as 25, the main body-portion of this plate, in the construction represented in said Figs. 6 to 9 inclusive, being curved so as to provide a pair of wing-like members 26 and 27 which conform to and register with the inner surface-ports of said post 20, as shown. The main body-portion of said lock-plate 25 is also provided with a slot or opening 28 of the same conformation as the said slot or opening 21 in the post 20. Extending in an upward direction from the said main body-portion of the said lock-plate 25 is an extension 29 which is provided with a pair of vertically extending side-lugs, as 30 and 31, said lugs with the said extension 29 providing a suitable guide in which is slidably retained a suitably formed flat lock-pin, key, or wedge, as 32. One of the said side-lugs, as

30, is formed with a vertically extending slot or elongated hole, as 33, and the said lock-pin, key, or wedge 32 is provided with a laterally projecting retaining stud, projection, or protuberance, as 34, which may form an integral part of said lock-pin, key or wedge, and which projects into and normally is slidably arranged in said slot or hole 33, as illustrated in Figs. 6 and 7 of the drawings. This stud, projection or protuberance 34 and the said slot or hole 33, as will be evident, limit the upwardly sliding movement of the lock-pin, key or wedge 32, and prevents its displacement from the guide in which said lock-pin, key, or wedge is adapted to slide, but when the lug or tongue 23 of the bracket-member 22 is inserted in and passed through the registering slots or openings 21 of the post 20, and 28 of the lock-plate 26, and the lower end-portion of the lock-pin, key, or wedge 32 is driven down into its binding and holding engagement with the opening 24 of the lug, tongue or extension 23 of the bracket-member 22, then the stud, projection, or protuberance 34 of the lock-pin, key, or wedge 32, leaves the said slot or elongated hole 33 of the side-lug 30, so as to bring the said lock-pin, key or wedge 32 into further binding relation with the inner surface-ports of the two side-lugs 30 and 31, so that the lock-pin, key, or wedge 32 is doubly secured against any upward displacement from its binding relation with the bracket-member 22, all of which will be clearly evident from an inspection of Fig. 8 of the drawings. The manner of securing these various parts described in connection with the construction of corner-post fastening illustrated in said hereinabove described Figs. 6 to 9 inclusive, is the same as that previously set forth in connection with the corner-post fastening illustrated in Figs. 1 to 5 inclusive, and it is therefore deemed unnecessary to further describe the operations of securing the parts shown in said Figs. 6, 7, 8 and 9 of the drawings in their assembled relations.

I am aware that changes may be made in the general arrangements and combinations of the various devices and parts, as well as in the details of the construction of the said parts, without departing from the scope of the present invention as set forth in the foregoing specification and as defined in the claims which are appended thereto. Hence, I do not limit my present invention to the exact arrangements and combinations of the various devices and parts as described in the said specification, nor do I confine myself to the exact details of the construction of the said parts as illustrated in the accompanying drawings.

I claim:—

1. In a corner-fastener for bedsteads, in combination with a tubular post provided

with an opening in its side, a lock-plate within said post, said lock-plate being provided with an opening in registration with the opening in said post, a bracket-member 5 provided with a perforated extension adapted to be inserted into and passed through the registering openings in said post and lock-plate so as to extend into the interior of said post, and means permanently but 10 slidably connected with said lock-plate, adapted to be brought into locked engagement with the perforated extension of said bracket-member, substantially as and for the purposes set forth.

15 2. In a corner-fastener for bedsteads, in combination with a tubular post provided with an opening in its side, a lock-plate within said post, said lock-plate being provided with an opening in registration with 20 the opening in said post, a bracket-member provided with a perforated extension adapted to be inserted into and passed through the registering openings in said post and lock-plate so as to extend into the interior 25 of said post, and a wedge-shaped key permanently but slidably connected with said lock-plate, adapted to be brought into locked engagement with the perforated extension of said bracket-member, substantially as and 30 for the purposes set forth.

3. In a corner-fastener for bedsteads, in combination with a tubular post provided with an opening in its side, a lock-plate within said post, said lock-plate being provided 35 with an opening in registration with the opening in said post, a bracket-member provided with a perforated extension adapted to be inserted into and passed through the registering openings in said post and lock- 40 plate so as to extend into the interior of said post, a wedge-shaped key permanently but slidably connected with said lock-plate, adapted to be brought into locked engagement with the perforated extension of said 45 bracket-member, and means connected with said lock-plate and in engagement with said key for limiting the slidable movements of said key, substantially as and for the purposes set forth.

50 4. In a corner-fastener for bedsteads, in combination with a tubular post provided with an opening in its side, a lock-plate within said post, said lock-plate being provided 55 with an opening in registration with the opening in said post, a bracket-member provided with a perforated extension adapted to be inserted into and passed through the registering openings in said post and lock-plate so as to extend into the interior of said 60 post, a wedge-shaped key permanently but slidably connected with said lock-plate, adapted to be brought into locked engagement with the perforated extension of said bracket-member, said key being provided 65 with a channel and stops formed at the re-

spective ends of said channel, and a stud-like element connected with said lock-plate extending into said channel and adapted to be brought into engagement with said stops for limiting the slidable movements of said key, substantially as and for the purposes set forth. 70

5. In a corner-fastener for bedsteads, in combination with a tubular post provided with an opening in its side, a lock-plate within said post, said lock-plate being provided with an opening in registration with the opening in said post, and bracket-member provided with a perforated extension adapted to be inserted into and passed through the registering openings in said post and lock-plate so as to extend into the interior of said post, a vertical extension connected with said lock-plate, and side-lugs connected with and projecting from said vertical extension toward the central axis of said post, said vertical extension and said side-lugs forming a guide, and means permanently arranged in said guide but adapted to slide therein, and adapted to be brought into locked engagement with the perforated extension of said bracket-member, substantially as and for the purposes set forth. 80

6. In a corner-fastener for bedsteads, in combination with a tubular post provided with an opening in its side, a lock-plate within said post, said lock-plate being provided with an opening in registration with the opening in said post, a bracket-member provided with a perforated extension adapted to be inserted into and passed through the registering openings in said post and lock-plate so as to extend into the interior of said post, a vertical extension connected with said lock-plate, and side-lugs connected with and projecting from said vertical extension toward the central axis of said post, said vertical extension and said side-lugs forming a guide, and a wedge-shaped key permanently arranged in said guide but adapted to slide therein, and adapted to be brought into locked engagement with the perforated extension of said lock-plate, substantially as and for the purposes set forth. 90

7. In a corner-fastener for bedsteads, in combination with a tubular post provided with an opening in its side, a lock-plate within said post, said lock-plate being provided with an opening in registration with the opening in said post, a bracket-member provided with a perforated extension adapted to be inserted into and passed through the registering openings in said post and lock-plate so as to extend into the interior of said post, a vertical extension connected with said lock-plate, and side-lugs connected with and projecting from said vertical extension toward the central axis of said post, said vertical extension and said side-lugs forming a 110

guide, a wedge-shaped key permanently arranged in said guide but adapted to slide therein, and adapted to be brought into locked engagement with the perforated extension of said lock-plate, and means connected with said lock-plate and in engagement with said key for limiting the slidable movements of said key, substantially as and for the purposes set forth.

- 10 8. In a corner-fastener for bedsteads, in combination with a tubular post provided with an opening in its side, a lock-plate within said post, said lock-plate being provided with an opening in registration with the opening in said post, a bracket-member provided with a perforated extension adapted to be inserted into and passed through the registering openings in said post and lock-plate so as to extend into the interior of said post, a vertical extension connected with said lock-plate, and side-lugs connected with and projecting from said vertical extension to-

ward the central axis of said post, said vertical extension and said side-lugs forming a guide, a wedge-shaped key permanently arranged in said guide but adapted to slide therein, and adapted to be brought into locked engagement with the perforated extension of said lock-plate, said key being provided with a channel and stops formed at the respective ends of said channel, and a stud-like element connected with said lock-plate extending into said channel and adapted to be brought into engagement with said stops for limiting the slidable movements of said key, substantially as and for the purposes set forth.

In testimony, that I claim the invention set forth above I have hereunto set my hand this 12th day of October, 1912.

RUBIN MAINKER.
